To all whom it may concern:

Be it known that I, William Zaiser, a citizen of the United States, residing at Rockville Centre, in the county of Nassau and State of New York, have invented a new, original, and ornamental Design for a Piano, of which the following is a specification, reference being had to the accompanying drawing, forming part thereof.

The figure is a perspective view of a piano, showing my new design, wherein the right-hand

I claim:

The ornamental design for a piano, as shown and described.

WILLIAM ZAISER.
